UNITED STATES PATENT OFFICE.

JAMES W. ARROWSMITH, OF MORRISTOWN, NEW JERSEY.

INSTEP-SUPPORT OR ARCH-PROP.

SPECIFICATION forming part of Letters Patent No. 717,523, dated January 6, 1903.

Application filed May 27, 1901. Serial No. 62,078. (No model.)

To all whom it may concern:

Be it known that I, JAMES W. ARROWSMITH, a citizen of the United States, residing at Morristown, in the county of Morris and State of New Jersey, have invented certain new and useful Improvements in Instep-Supports or Arch-Props; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The objects of this invention are to provide an instep-support or arch-prop which will be more elastic and comfortable for the foot, to enable the lateral upturned elastic tongues to be of one piece with the body portion, to provide for strengthening or stiffening the body portion by a brace on the under side, and to secure other advantages and results, some of which may be referred to hereinafter in connection with the description of the working parts.

The invention consists in the improved instep-support or arch-prop and in the arrangements and combinations of parts of the same, all substantially as will be hereinafter set forth, and finally embraced in the clauses of the claim.

Referring to the accompanying drawings, in which like letters of reference indicate corresponding parts in each of the several figures, Figure 1 is a perspective view of my improved support. Fig. 2 is a plan. Fig. 3 is a perspective view looking nearly endwise of the support. Fig. 4 is a longitudinal section showing a reinforcing-brace standing away from the body portion, and Fig. 5 is a cross-section showing a brace in close contact with the body portion.

In said drawings, *a* indicates the body portion of my improved support, which is formed out of sheet metal, preferably German silver, of a proper degree of stiffness. Said body portion comprises a plate of an irregularly oblong shape, having one end *b* rounded at the edge and slightly concaved at its upper side to afford a seat for the heel of the wearer's foot, while the opposite end *b* is cut on a

transverse line and adapted to lie just back of the ball of the foot. Intermediate the said ends of the plate its middle part is bent or curved upward, as at *c*, to form an arch conforming more or less closely to the normal arch of a foot at the instep. Said plates, it will be understood, are made in rights and lefts, according to the two feet of a person, and the inner margin of each plate or margin adapted to lie next the other foot when the plate is in use. Has along the middle arched part of the plate a series of slits *e*, extending transversely inward from the edge of the plate and forming tongues *d*, which are then curved or bent upward out of their normal plane. The side or margin of the plate thus slitted as described is curved or rounded outward between its ends, and thus the tongues *d* formed are of different lengths, the middle ones being longer than the end ones. In bending or curving up the tongues *d* the middle longer ones are deflected the most, those on each side being bent less and less as they are farther from the middle ones until the end short tongues are scarcely changed from the plane of the plate. As the tongues *d* are bent upward they separate at their edges, so that freedom of independent flexing is permitted and an elasticity or springiness secured which is especially adapted to the purpose of comfortably supporting the foot. It will be understood that the tongues *d* press against and support the inner upper part of the arch or instep at the inner side of the foot for the following reason: When in the breaking down of the arch of a foot the astragalus bone forces itself between the os calcis and the scaphoid, the resistance offered by the cuboid causes both the astragalus and the scaphoid to project outward as well as downward. It is therefore necessary in all cases, especially those of long standing, to apply not only a support from underneath, but also a pressure from the side to supplement the relaxed tension of the ligaments that have become stretched, and, furthermore, as the projection of the bones mentioned is not always equal in extent it is desirable to have a support that will present a varying pressure at different points, as needed.

This is accomplished by my series of tongues,

which can flex or bend independently to meet requirements. Moreover, the slits *e* in the side of the body portion or plate permit and facilitate an upbending of that edge or margin of the plate to fit the foot, so that the mechanical construction is much more easily effected.

To the under surface of the body portion or plate *a* I fasten a reinforcing-strip *f*, disposed longitudinally of the body-plate and overlapping at its edge the inner ends of the slits *e*, separating the tongues *d*, or at least the inner ends of the middle or longer slits, as shown in Figs. 2 and 5. This strip *f* is riveted to the body-plate *a* in any suitable manner, as indicated at *f'*, and may either lie flat against the body-plate *a*, as shown in Fig. 5, or it may be separated therefrom at its middle, as at *g'* in Fig. 4, to secure a desired degree of elasticity. This reinforcing-strip enables the body-plate to be made light enough so it can be bent or peened by the orthopedist into proper shape to exactly fit the individual patient and yet not break transversely across because of the slits *e*. If no reinforcing-plate were employed, the plate *a* would have to be so thick and heavy to resist breaking across from the slits *e* that it would lose its elasticity and be unyielding to the action of the foot. By my strip *f* at the bases of the tongues I prevent the slits between said tongues from extending or cracking further under the action of a foot upon the prop, and still I do not sacrifice elasticity.

Having thus described the invention, what I claim as new is—

1. An instep-support or arch-prop comprising a plate of resilient metal having the portion between its ends curved upwardly to fit

the under surface of the normal arch of the instep and having a side portion curved upwardly to fit the side surface of the normal arch of the instep, the side portion consisting of a series of tongues separated by slits, said slits extending into the body portion of the plate, and a reinforcing-strip secured to the under surface of the plate and extending longitudinally thereof, the reinforcing-strip being so located that one of its side edges overlaps the inner ends of the slits and bears against the tongues; substantially as described.

2. An instep-support or arch-prop comprising a plate of resilient metal having the portion between its ends curved upwardly to fit the under surface of the normal arch of the instep, and having a side portion curved upwardly to fit the side surface of the normal arch of the instep, the side portion consisting of a series of tongues separated by slits, said slits extending into the body portion of the plate, and a reinforcing-strip extending longitudinally of the plate, and secured at its ends to the under surface of the plate, the reinforcing-strip being less curved than the plate, so that its middle portion is not in contact therewith, the reinforcing-strip being so located that one of its side edges overlaps the inner ends of the slits; substantially as described.

In testimony that I claim the foregoing I have hereunto set my hand this 21st day of May, 1901.

JAMES W. ARROWSMITH.
